UNITED STATES PATENT OFFICE.

WILLIAM BARNES, OF SAN FRANCISCO, CALIFORNIA.

INTERNAL-COMBUSTION ROTARY ENGINE.

1,018,953.

Specification of Letters Patent.

Patented Feb. 27, 1912.

Application filed June 15, 1909. Serial No. 502,349.

To all whom it may concern:

Be it known that I, WILLIAM BARNES, a citizen of the United States, residing at San Francisco, in the county of San Francisco and State of California, have invented new and useful Improvements in Internal-Combustion Rotary Engines, of which the following is a specification.

My invention relates to internal combustion rotary engines, and its principal objects are to produce an engine of the class described which will be compact in form; light in weight; of high power, and which in its operation will give a minimum of vibration.

An embodiment of my invention is illustrated by the accompanying drawings, which are for illustrative purposes only and are not turned to any particular scale. These drawings form a part of this specification, and in which drawings—

Figure 1 is a front elevation partly in section, and Fig. 2 is a sectional side elevation.

Referring more particularly to the drawings the numeral 1 represents an annular frame rotatably mounted on the stationary shafts 2 and 3. Mounted on the frame 1 is a plurality of cylinders 4, preferably equally spaced apart, and provided to have an oscillatory movement by means of suitable pivotal bearings at 5. Operable in each cylinder is a suitable piston 6 secured in any suitable manner to a tubular piston rod 7. These tubular piston rods operate in bearings 8 on the inner heads of each of the cylinders, and the inner ends of these piston rods are journaled to the crank-pin 9 on the crank 11 in a manner as will hereinafter be more fully described. This crank 11 I have shown rigidly secured to the shaft 2.

I have shown the cylinders mounted in staggered relation to each other so that the piston rod of each may be mounted to have a direct thrust on the crank-pin 9.

The shaft 3 I have shown tubular in construction, and it serves as an inlet for the explosive fluid from any suitable source of supply. Connected with this tubular shaft 3 is the pipe 12 of such form as to convey the explosive fluid to a point in line with the axis of the crank-pin 9. Connected on this pipe 12 is the hood 13. I have shown this

connection by means of the slip-joint 10. This hood 13 is secured in any suitable manner to the casing of a chamber at the end of the piston rod mounted on the outer end of the crank-pin 9.

I show a preferred form of construction of the mounting of the piston rods 7 on the crank-pin 9. The journals of these piston rods adjoin each other, as shown in Fig. 2, and each journal is constructed with a bearing ring 14, which bears on the crank-pin 9. This bearing ring 14 is surrounded by the ring 15 and these two rings form the inner and outer walls of a chamber. The rings 14 and 15 are joined by bridges 16 so that the two rings and the bridges form a rigid structure. The tubular piston rod 7 is secured to the outer ring and an opening is provided connecting the chamber between the two rings and the tubular piston rod.

It will be seen that with the piston rod journals mounted adjacent each other on the crank-pin 9 the chamber of one of the mountings will register with the chamber of the adjoining one and form one continuous chamber 17 with which the tubular piston rods of each of the cylinders connect.

I provide that the chamber in the piston rod journal at the innermost end of the crank-pin 9 be closed at its one side, as shown in Fig. 2, so as to close one end of the chamber 17. The chamber on the piston rod journal at the outermost end of the crank-pin is provided to open into the hood 13. By this construction it will be seen that explosive fluid can be caused to flow from the pipe 12 into the hood 13; from the hood 13 into the chamber 17, and from the chamber 17 into each of the tubular piston rods 7.

As the cylinders and their operative mechanism are alike in construction and in operation a description of one of them will suffice.

Opening from the tubular piston rod 7 is the port 21. This port is so positioned in the piston rod 7 that it is open in the innermost part of the cylinder only when the piston 6 is in the outermost part of the cylinder. At all other times of the stroke of the piston in the cylinder the port 21 is closed by the bearing 8, which is of sufficient length to cover this port 21 during

the stroke of the piston in the innermost end of the cylinder.

In the wall of the cylinder is an inlet passage 20. This passage has an opening in the cylinder near the innermost end of the said cylinder, and a port 19 opening into the cylinder chamber near the center thereof. This port 19 is only open when the piston is at the innermost part of its stroke and closed by the said piston during all the other parts of the stroke of the piston. In the wall of the cylinder, and preferably at a point diametrically opposite the port 19, is the exhaust port 18. This port 18 is open only when the piston is at the innermost part of its stroke and closed by the piston during all the other parts of the stroke of the piston.

As the cylinder moves inwardly on the piston the port 21 will be opened into the cylinder and a flow of explosive fluid will take place from the tubular piston rod into the cylinder between the piston and the cylinder's inward head. Then as the cylinder returns and moves outwardly on the piston rod the port 21 will be closed and the explosive fluid that was admitted into the inner end of the cylinder will be forced through the inlet ports 19 and 20 into the outer end of the cylinder between the piston and the outward cylinder head.

On the piston 6 I place the baffle plate 22 of any convenient form and adapted to deflect the flow of the explosive fluid as it enters from the inlet port toward the outer end of the cylinder and away from the open exhaust port. When the cylinder again moves inwardly this explosive fluid admitted into the outer end of the cylinder through the port 19 will be compressed and ready for ignition when the end of the stroke is reached. When the combustion takes place the outer end of the cylinder will be driven away from the piston, and it in moving will impart motion to the annular frame to which it is attached. When the cylinder reaches a desired point in its movement the piston 6 will pass the exhaust port 18 and the port will be opened allowing the cylinder to be cleared of the combustion gases. At the same time the port 19 will be opened admitting a fresh charge of explosive fluid.

As a means of igniting the explosive fluid when desired I provide any one of the usual devices, common in such use and generally known as a "spark plug" 23, one point of which is connected in any suitable manner to the one side of any source of electrical supply through the medium of the cylinder casing, the rotary member 1 and the shaft 2. The other point of the spark plug I connect by the wire 24 to the plate 25 at any suitable point on the rotary member 1 and

insulated therefrom. Conveniently mounted adjacent the rotary member 1 is the trigger 26, which is conveniently connected with the second side of the source of electrical energy, as by means of the conductor 27. As the member 1 revolves, and the plate 25 makes contact with the trigger 26, a circuit will be completed from the source of electrical supply through the spark plug 23 and by the operation of the spark plug the compressed explosive fluid will be ignited.

It will be seen that by providing for the mounting of the trigger in any suitable manner so that it may move to points so as to cause combustion of the explosive fluid in the cylinder when the cylinder is on either one or the other side of the center line of the crank 11, or approximately at the points A or B as shown in Fig. 1, the engine may be made to rotate in either direction as desired.

If the trigger should be so placed so as to complete the circuit from the source of electrical supply and cause the combustion of the explosive fluid when the cylinder is at the point approximately at A the cylinder will be forced away from the piston to the left of the center of the crank, as shown in the drawing, and the member 1 will be caused to rotate in the direction as indicated by the arrow. Should the trigger be so placed as to cause the combustion of the explosive fluid when the cylinder is approximately at the point B the cylinder will be forced away from the piston to the right of the center of the crank, as shown in the drawing, and the member 1 will be caused to rotate in the direction opposite to that indicated by the arrow.

I do not limit myself to the precise construction and arrangement of parts herein described and shown in the drawings, as I desire to avail myself of such modification and equivalents as fall properly within the spirit of my invention.

Having thus described my invention, what I claim as new and desire to secure by Letters Patent is:

1. In a valveless rotary explosive engine, a frame rotatably mounted on fixed shafts, a plurality of cylinders mounted thereon with oscillatory movements, each of said cylinders provided with a piston, a stationary crank, a tubular piston rod connected to each of said pistons and revolvably mounted on said stationary crank, means common to all the piston rods for admitting explosive fluid thereto, and means controlled by the movement of the cylinders for admitting explosive fluid from said tubular piston rods to said cylinders, substantially as described.

2. In a valveless rotary explosive engine, a frame rotatably mounted on fixed shafts, a plurality of cylinders mounted thereon

with oscillatory movements, each of said cylinders provided with a piston, a stationary crank, a tubular piston rod connected to each of said pistons and revolvably mounted on said stationary crank, each piston rod having an inlet passage for explosive fluid, ports in said rods for the passage of explosive fluid from said tubular piston rods to said cylinders, and said ports being controlled by the movements of said cylinders, substantially as described.

3. In a valveless rotary explosive engine, a frame rotatably mounted on fixed shafts, a plurality of cylinders mounted thereon with oscillatory movements, each of said cylinders provided with a piston, a stationary crank, a tubular piston rod connected to each of said pistons and revolvably mounted on said stationary crank, each piston rod having an inlet passage for explosive fluid, ports in said rods for the passage of explosive fluid from said tubular piston rods to said cylinders, said ports being controlled by the movements of said cylinders, exhaust ports in the cylinders, and said exhaust ports being controlled by the relative movements of said cylinders and pistons, substantially as described.

4. In a valveless rotary explosive engine, a frame rotatably mounted on fixed shafts, a plurality of cylinders mounted thereon with oscillatory movements, each of said cylinders provided with a piston, a stationary crank, a tubular piston rod connected to each of said pistons and revolvably journaled on said crank, chambers provided in said journals, openings from said chambers to said tubular piston rods, means for admitting explosive fluid to said chambers, and means controlled by the movement of the cylinders for admitting the fluid from the tubular rods to the cylinders, substantially as described.

5. In a valveless rotary explosive engine, a frame, fixed shafts rotatably supporting the same, a crank connected with the shafts, a cylinder mounted on said frame with oscillatory movement, a piston in said cylinder, a tubular piston rod connected to said piston and to the crank, a sleeve on said cylinder slidable on said tubular piston rod, a port in said tubular piston rod, said port opening into said cylinder when said cylinder is in one part of its movement, and said port closed in said sleeve when said cylinder is in another part of its movement, and means for introducing the motive fluid into said piston rod, substantially as described.

6. In a valveless rotary explosive engine, a frame, fixed shafts rotatably supporting the same, a fixed crank, a cylinder pivoted to the frame at its outer end, said cylinder having a sleeve extending from its inner

end, a piston in said cylinder, a tubular piston rod journaled to the crank and passing through the sleeve, means for delivering motive fluid to said tubular rod, said rod having an outlet port for delivering the fluid to the cylinder when said cylinder is at the inner end of its movement, said sleeve covering the port in other positions of the cylinder, said cylinder having a channel with its one port opening into said cylinder between a head of said cylinder and said piston and with its other port opening into said cylinder on the outward side of said piston when said cylinder is at the outer end of its movement, an exhaust port in said cylinder, and said exhaust port controlled by the relative movement of said cylinder and piston, substantially as described.

7. In a valveless rotary explosive engine, a frame rotatably mounted on fixed shafts, a plurality of cylinders mounted thereon with oscillatory movements, each of said cylinders provided with a piston, a stationary crank, a tubular piston rod connected to each of said pistons and revolvably mounted on said stationary crank, an inlet passage in each of said piston rods for explosive fluid, ports for the passage of explosive fluid from said tubular piston rods to said cylinders, exhaust ports in said cylinders, said ports for the passage of explosive fluid from said tubular piston rods and said exhaust ports being controlled by the relative movement of said cylinders and pistons, substantially as described.

8. In a valveless rotary explosive engine, a frame rotatably mounted on fixed shafts, a cylinder mounted thereon with an oscillatory movement, said cylinder provided with a piston, a stationary crank, a tubular piston rod connected to said piston and revolvably mounted on said stationary crank, means for admitting explosive fluid to said tubular piston rod, means controlled by the movement of the cylinder for admitting explosive fluid from said tubular piston rod to said cylinder, means for igniting said explosive fluid in said cylinder, and an exhaust port controlled by the relative movement of said piston and cylinder for freeing said cylinder of the gases of combustion, substantially as described.

9. In a valveless rotary explosive engine, a frame rotatably mounted on fixed shafts, a plurality of cylinders mounted thereon with oscillatory movements, each of said cylinders provided with a piston, a stationary crank, a tubular piston rod connected to each of said pistons and revolvably mounted on said stationary crank, means for admitting explosive fluid to said tubular piston rods, means controlled by the movement of the cylinders for admitting explosive

fluid from said tubular piston rods to said cylinders, means for igniting said explosive fluid in said cylinders, and an exhaust port in each of said cylinders controlled by the relative movement of said piston and cylinder for freeing said cylinder of the gases of combustion, substantially as described.

In testimony whereof I have affixed my signature in the presence of two witnesses this 3rd day of June 1909.

WILLIAM BARNES.
